UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed November 5, 1925. Serial No. 66,963.

My invention relates generally to internal exhaust port 14. Ports 13 and 14 are arranged so that they are uncovered and open only when the pistons 15 that are arranged for reciprocatory movement within the combustion chambers in cylinders 10 are at the lower or outer ends of their strokes. 55

The principal objects of my invention are to generally improve upon and simplify the 10 construction of the existing forms of two stroke cycle internal combustion engines, to provide a power unit wherein the fuel charge volumes are pumped into the combustion chambers by a member that functions as a compensating reciprocating counterforce, to provide a piston valve for controlling the admission of charge volumes to the pump, to combine with an engine of the character referred to a counterbalanced 15 crank shaft and to provide connections between the combined pumping piston and counterforce member and the piston valve and the crank shaft whereby said piston valve and pumping piston will function in 20 proper time relation to each other and to the power pistons in the combustion cylinders that are served by said pumping piston. 25

With the foregoing and other objects in view, my invention consists in certain novel 30 features of construction and arrangement of parts that will hereinafter be more fully described and claimed and illustrated in the accompanying drawing, in which—

Fig. 1 is a vertical transverse section 35 taken through the center of one of the power cylinders of my improved engine and through the centers of the pumping and piston valve cylinders that are associated therewith. 40

Fig. 2 is a top plan view of one of the power units of my improved engine with the cylinder head block removed. 45

Fig. 3 is a vertical section taken approximately on the line 3—3 of Fig. 1.

Referring by numerals to the accompanying drawing, 10, 10 designate power or combustion cylinders, the chambers within which are connected at their head or inner ends by a common compression and combustion 50 clearance space such as 11 that is formed in the underside of the cylinder head block 12. One of these combustion cylinders is provided with a charge volume inlet port 13 and the other cylinder is provided with an

55 The cylinders 10 surmount a crank case 16 having suitably arranged bearings 17 for a crank shaft 18 and said crank being provided with tandem crank pins such as 19 that are coaxial and which are connected to 60 crank shaft 18 by conventional crank arms 20. These crank arms are provided with suitable counterweights 21, the same being arranged diametrically opposite to the tandem crank pins 19. The power pistons 15 70 are separately connected to the crank pins 19 by suitable connecting rods 22.

Secured in any suitable manner to crank 75 case 16 and arranged substantially at right angles or 90° from the axes of cylinders 10 is a charge volume pumping cylinder 23 within which is arranged for reciprocatory movement a combined piston and counterweight 24. This combined piston and counterweight is connected by a connecting 80 rod 25 to a crank pin 26 that is connected to and disposed between the inner pair of crank arms 21 and said crank pin occupying the same radial plane with the tandem crank pins 19 but being located nearer to the axis 85 of the crank shaft 18 than the axes of said tandem crank pins. Thus the throw or circular path of travel of crank pin 26 is somewhat less than the throw or circular path of 90 travel of the tandem crank pins 19.

Occupying an inclined position between cylinders 10 and pumping cylinder 23 is a piston valve cylinder 27, the inner end of which is suitably connected to crank case 16 and formed on said valve cylinder is an 95 annular housing 28 that incloses an annular chamber 29 and connecting the latter with the valve chamber 30 in housing 27 are charge volume inlet ports 31. Leading from a suitable source of supply to the annular chamber 29 is a charge volume supply duct 32. The outer end of cylinder 23 is provided with a port 33, and leading therefrom and communicating with the outer end of piston valve cylinder 27 is a duct 34. From 100 the outer end of the piston valve cylinder, this duct is extended to one of the pair of combustion cylinders that form another 105

power unit of the engine, and said duct, which is designated by the numeral 35, communicates with the inlet port 13 into the combustion cylinder.

- 5 Arranged for reciprocatory movement within the piston valve chamber 30 is a piston valve 36, and arranged between the wrist pin 40 of said piston valve, and a wrist pin 39 that is seated in a pair of lugs 10 37 that are formed on the inner end of connecting rod 25, is a connecting rod 38.

In the operation of my improved engine, a gaseous fuel charge compressed within common clearance chamber 11 is ignited as 15 the pistons 15 pass high center, and as a result of the rise in pressure following combustion of the compressed fuel charge, the pistons are forced downward on their power stroke.

- 20 As the pistons approach the lower or outer ends of their stroke, the inlet and exhaust valves 13 and 14 respectively are uncovered and opened, and as such action takes place, a pumped charge volume for the pumping cylinder of another one of the engine units enters inlet port 13 from duct 35 and passes upwardly through the corresponding combustion chamber, thence through the common clearance chamber and thence downwardly 25 through the combustion chamber having the exhaust port 14, and this incoming charge drives before the burnt gases and products of combustion and which latter escape or discharge through exhaust port 14. On the 30 succeeding upward travel of the pistons, the fuel charge thus delivered into the combustion chambers is compressed in the common clearance chamber 11 until at the point of highest compression, said fuel charge is ignited and the cycle of operation is repeated. Through the connecting rods 22, the reciprocating motion of the power pistons is transmitted to crank shaft 18, and as the latter rotates, the pumping piston 24 and piston valve 36 will be reciprocating in their respective cylinders.

35 Inasmuch as the crank and wrist pin 39, to which the crank end of connecting rod 38 is connected, is slightly late in rotation and in relation to the dead center line between the crank shaft axis and the axis of the piston valve wrist pin 40, the piston valve 36 on its outward stroke will move to a position to open inlet ports 31 slightly after pumping piston 24 starts on its outward stroke, thus providing the desired lag in opening, so that, as the piston valve continues to move outwardly, said ports 31 are opened, thereby admitting a charge volume 40 from duct 32 and this charge volume will be drawn through duct 34 and port 33 into the chamber within pumping cylinder 23 in front of the piston 24 therein.

45 On the inward travel or strokes of pumping piston 24 and piston valve 36, the latter

will close ports 31 slightly after the pumping piston 24 starts on its inward stroke, thus providing the desirable valve closing lag, and as the pumping piston moves inward the charge volume previously drawn into 70 the pumping chamber will be forced outwardly through port 33 and thence through ducts 34 and 35 to the combustion chambers within the cylinders 10 of another one of the engine power units.

75 Thus it will be seen that I have provided a two stroke cycle internal combustion engine power unit that involves a pair of combustion or power cylinders, a combined pumping and counter force member and a piston valve, and which combined pumping and counter force member and piston valve are directly connected to the crankshaft of the engine in such a manner as to function in proper time relation to each other and to the combined 80 chambers that are served by the charge volume pump and the parts of the engine being constructed and arranged so as to establish perfect reciprocative force alternation and balance in operation.

85 It will readily be understood that minor changes in the size, form and construction of the various parts of my improved engine may be made and substituted for those herein shown and described without departing 90 from the spirit of the invention, the scope of which is set forth in the appended claims.

95 I claim as my invention:

1. In a two stroke cycle internal combustion engine, a power unit comprising a pair 100 of combustion cylinders, the head ends of which are connected by a common compression and combustion clearance chamber, pistons arranged for operation within said combustion cylinders, a charge volume pumping cylinder, a piston arranged for reciprocatory movement therein, a piston valve for controlling the admission of gaseous fuel into said pumping cylinder, which piston valve occupies an angular position between the 105 planes occupied by said combustion cylinders and said charge volume pumping cylinder, a crank shaft and connections between the pistons in the combustion cylinders, the pumping piston and the piston valve and 110 said crank shaft.

- 115 2. In a two stroke cycle internal combustion engine, a power unit comprising a pair of combustion cylinders, the head ends of which are connected by a common compression and combustion clearance chamber, pistons arranged for operation within said combustion cylinders, a charge volume pumping cylinder, a piston arranged for reciprocatory movement therein, a piston valve for controlling the admission of gaseous fuel into said pumping cylinder, which piston valve occupies an angular position between the planes 120 occupied by said combustion cylinders and said charge volume pumping cylinder, a 125

crank shaft, connections between the pistons in the combustion cylinders, the pumping piston and the piston valve and said crank shaft, and a charge volume transfer duct 5 arranged between the pumping cylinder and the piston valve cylinder, and leading from said piston valve cylinder.

3. In a two stroke cycle internal combustion engine, a power unit comprising a pair 10 of combustion cylinders, the head ends of which are connected by a common compression and combustion clearance chamber, pistons arranged for operation within said combustion cylinders, a charge volume pumping 15 cylinder, a piston arranged for reciprocatory movement therein, a piston-valve for controlling the admission of gaseous fuel into said pumping cylinder, a crank shaft having tandem crank pins to which the pistons in 20 the combustion cylinders are connected, a crank pin forming a part of said crank shaft and arranged between said tandem crank pins, connections from the pumping piston and the piston valve to the intermediate 25 crank pin, the axis of the intermediate crank pin being located at a different distance from the axis of the crank shaft than is the axes of the said tandem crank pins from the axis of the crank shaft and the axes of 30 compression and combustion cylinders being angularly disposed radially with the axis of the crank shaft 90° of the axis of said pumping cylinder.

4. In a two stroke cycle internal combustion engine, a power unit comprising a pair 35 of combustion cylinders, the head ends of which are connected by a common compression and combustion clearance chamber, pistons arranged for operation within said combustion cylinders, a charge volume pumping 40 cylinder arranged in a plane substantially at right angles to the plane occupied by the combustion cylinders, a pumping piston arranged for operation within said pumping cylinder, a piston valve cylinder occupying an inclined position between the combustion cylinder and the pumping cylinder, a piston valve arranged for operation 45 within the piston valve cylinder, a duct arranged between the pumping cylinder and the piston valve cylinder, a crank shaft, separate connections from the pistons in the combustion cylinders, the pumping piston and the piston valve and said crank shaft, 50 there being a radially tandem arrangement of crank pins of the crank shaft to each pair of 90° angularly disposed combustion and pumping cylinders, the axis of the pair of 55 crank pins to which the adjacent pair of combustion cylinder pistons are connected

being disposed on a line parallel with the axis of the crank shaft, the piston valve being connected to the crank shaft, the through a wrist pin held in the crank end of the connecting rod attaching the pump 65 piston to the crank shaft and the position of said crank end wrist pin held in the pump cylinder piston connecting rod, being offset late rotatively relative to the line intersecting the crank shaft axis and the axis of the 70 piston end unit pin of the piston valve.

5. In a two stroke cycle internal combustion engine, a unit comprising a pair of combustion cylinders, a fresh charge pump cylinder and a piston valve cylinder, piston 75 within each of the four cylinders, a crank shaft having three crank pins to each unit of four cylinders, connection between the four pistons and the three crank pins of the crank shaft, the two combustion cylinders 80 being adjacent to each other and having axes parallel, the fresh charge pump cylinder being radially disposed relative to the pair of adjacent combustion cylinders, with its axis 90° apart from the axes of the combustion 85 cylinders, the piston valve cylinder being angularly disposed in the same radial plane as the combustion and pump cylinder and located between the said combustion and pump cylinders, the axes of the combustion 90 cylinders, the pump cylinder and the piston valve cylinders intersecting the axis of the crank shaft, the three crank pins of the crank shaft adapted to each unit of four cylinders being arranged with two pins axially tandem and with a given radial distance 95 between their axes and the axis of the crank shaft, one crank pin between and separating the axially tandem pair of crank pins, the said intermediate crank pin axis being of 100 less radial distance from the axis of the crank shaft, than is the radial distance between the axes of the axially tandem pair of crank pins and the axis of the crank shaft, a wrist pin located in the crank end part 105 of the connecting rod that joins the pump piston to the intermediate crank pin of the least crank throw, the crank end of the piston valve connecting rod being attached to said wrist pin, and the axis of said wrist 110 pin joining the pump piston connecting rod and the piston valve connecting rod, being offset late relative to crank shaft direction of rotation to the dead center line intersecting the axis of the crank shaft and the 115 axis of the wrist pin in the piston valve to which the piston end of the piston valve connecting rod is connected.

In testimony whereof I affix my signature.

EVERETT R. BURTNETT.
